UNITED STATES PATENT OFFICE.

FRANK M. GINGER, OF ELDORADO, KANSAS.

SIGN.

Application filed May 26, 1925. Serial No. 33,028.

To all whom it may concern:

Be it known that I, FRANK M. GINGER, a citizen of the United States, residing at Eldorado, in the county of Butler and State of Kansas, have invented certain new and useful Improvements in Signs, of which the following is a specification, reference being had to the accompanying drawing.

This invention relates to certain improvements in signs and it is an object of the invention to provide a device of this general character embodying means whereby the notice disclosed thereby may be changed in accordance with the requirements incident to the particular use of the sign.

Another object of the invention is to provide a sign of this character including a main sheet or body and a swinging plate or leaf associated therewith, the same coacting in a manner whereby differing notices may be exposed.

The invention consists in the details of construction and in the combination and arrangement of the several parts of my improved sign whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation illustrating a sign constructed in accordance with an embodiment of my invention;

Figure 2 is a view in side elevation of the structure as illustrated in Figure 1;

Figure 3 is a view in elevation of the sign as disclosed in Figure 1 with the movable or swinging leaf in a second position;

Figure 4 is a view in side elevation of the structure as illustrated in Figure 3;

Figure 5 is a view in elevation illustrating a sign constructed in accordance with a further embodiment of my invention;

Figure 6 is a side elevation of the structure as illustrated in Figure 5;

Figure 7 is a front elevation of the sign illustrated in Figure 5 with the movable or swinging leaf in a second position;

Figure 8 is a view in side elevation of the structure as illustrated in Figure 7.

As disclosed in Figures 1 to 4, 1 denotes

a plate of desired dimensions and configuration and which is provided with the suitably positioned outstanding ears 2 through which suitable holding members are adapted to be directed to maintain said plate in applied position as upon the side wall of a car or the like. At opposed points the sides of the plate 1 are provided with the outstanding flanges or webs 3, each of said flanges or webs 3 immediately adjacent to the plate 1 being provided with a slot 4 the upper portion of which being enlarged to provide a substantially right triangular opening 5, the edge of such opening defining the hypotenuse of such opening being disposed on an outward and downward incline.

A swinging leaf or plate 6 is employed in connection with the plate 1, said plate 6 being of requisite dimensions and configuration and provided at one longitudinal marginal portion with oppositely disposed outstanding flat arms 7 coplanar with the plate 6 which, when the plate 6 is swung downwardly, are adapted to be received within the lower or restricted portion of the slot 4 so that said plate, when in such lowered position, is held against swinging movement. When the plate 6 is moved upwardly or in a direction to position the arms 7 within the enlarged portions 5 of the slots 4 the plate 6 may be swung upwardly and reversed to have close contact with the plate 1 and more especially the upper portion thereof.

The outer or free marginal portion of the plate 6 at substantially the longitudinal center thereof is provided with a slot 8 disposed at right angles to the axis about which the plate 6 swings and the outer end of the slot 8 is continued by a perpendicularly related extension slot 9, the marginal portion of the plate 6 defining the outer edge of said extension slot 9 having produced therein a notch or recess 10 opening into the extension slot 9 and positioned at one side of the slot 8.

When the plate 6 is swung upwardly an outstanding lug 11 carried by the upper portion of the plate passes through the slot 9 and as the arms 7 drop within the lower or restricted portions of the slots 4 said lug is positioned at the outer end of the slot 8 so that upon lateral or sidewise movement being imparted to the plate 6, said lug will be received within the extension slot 9 and when the notch or recess 10 is positioned

above said lug 11, the plate 6 will further drop to permit said lug 11 to be received within said notch or recess whereby the plate when in its upper position is held 5 against lateral movement. The lug 11 is of a length to project beyond the outer face of the plate or leaf 6 when said plate is engaged therewith and the outer end of said lug is provided with a cross head 12 extending 10 in the same general direction as the slot 8 and of a length in excess of the width of the slot 9 so that at any point along the slot 9 the plate or leaf 6 is held against downward swinging movement.

15 To facilitate the lateral movement of the plate or leaf 6 to bring the lug 11 within the slot 10 an end marginal portion of the plate or leaf 6 is provided with a recess or notch 14 which receives, upon such lateral 20 movement, a portion of a web or flange 3 above the enlarged portion 5 of the slot 4.

The plate 1 above and below its vertical center is provided with suitable legends or indicia 15 giving desired information while 25 the opposite faces of the plate or leaf 6 are also provided with suitable legends or indicia 16. When the plate or leaf 6 is in its lowered position the lower legend or indicia 15 is concealed by the plate or leaf 6 with the legend or indicia 16 on a face of 30 said leaf or plate 6 exposed and when the plate or leaf 6 is in its raised position the upper legend or indicia 15 on the plate 1 is concealed and the legend or indicia 16 on the 35 opposed face of the leaf or plate 6 is exposed.

If desired a conventional seal 18 or its equivalent may be disposed through the slot 8 and a suitable opening 19 in the plate 1 to 40 further maintain the plate or leaf 6 in its raised position and to provide means to denote unauthorized adjusting of such plate or leaf 6.

45 In the embodiment of my invention as illustrated in Figures 5 to 8, the plate 1' is of suitable design and dimensions and is provided at its lower portion with an outstanding foot or bracket 20 to provide means whereby the plate may be bolted or otherwise secured to a tank car bolster, running board or other desired support. Operatively engaged with the plate 1' is the plate 6', such engagement being substantially the 50 same as hereinbefore particularly recited in connection with the first embodiment of my invention. The upper portion of the plate or leaf 6' to one side of its longitudinal center is provided with a zigzag slot 21 disposed in a general direction at right angles 55 to the axis about which the plate 6' swings. The upper end of this slot 21 is provided with a laterally and outwardly disposed extension 22 while the opposite end portion thereof is enlarged, as at 23, to permit ready 60 passage therethrough of the head 24 carried 65

by the outer end portion of the lug 25 extending outwardly from the plate 1'. When the plate 6' is swung into its upper position, the lug 25 and head 24 thereof is passed through the lower enlarged portion 23 of the slot 21 and as the plate drops downwardly within the slots 4' the lug 25 will be received within the lateral extension 22 whereby said plate or leaf 6' will be effectively maintained in such raised or elevated position. The head 24 is of a width or diameter in excess of all portions of the slot 21 with the exception of the inner enlarged portion 23.

70 I also find it of particular advantage to provide the leaf or plate 6 or 6' with the suitably positioned slots 26 to permit the ready application to said leaf or plate of a destination or consignee card as particularly indicated by dotted lines in Figure 3 75 of the accompanying drawings. I also find it of advantage to provide the adjacent end portions of the plate 1' and the foot or bracket 20 with the reinforcing or strengthening corrugation 27.

80 From the foregoing description it is thought to be obvious that a sign constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation 85 of the several parts herein shown in carrying out my invention in practice except as 90 hereinafter claimed.

95 I claim:—

100 1. A signal comprising, in combination, a plate provided with spaced outstanding ears, said ears being provided with slots having corresponding ends enlarged, a second plate having outstanding arms insertible through the slots of the ears of the first plate, said arms when within the enlarged portions of the slots permitting the second plate to be 105 swung to overlie one or the other end portion of the first plate, said arms when within the restricted portions of the slots holding the second plate against rotation.

110 2. A signal comprising, in combination, a plate provided with spaced outstanding ears, said ears being provided with slots having corresponding ends enlarged, a second plate having outstanding arms insertible through the slots of the ears of the first plate, said arms when within the enlarged portions of the slots permitting the second plate to be 115 swung to overlie one or the other end portions of the first plate, said arms when within the restricted portions of the slots holding the second plate against rotation, and 120

means for holding the second plate against movement when the arms of said plate are engaged within the restricted portions of the slots.

5. 3. A signal comprising, in combination, a plate provided with spaced outstanding ears, said ears being provided with slots having corresponding ends enlarged, a second plate having outstanding arms insertible through the slots of the ears of the first plate, said arms when within the enlarged portions of the slots permitting the second plate to be
10. swung to overlie one or the other end por-

tion of the first plate, said arms when within the restricted portions of the slots holding the second plate against rotation, the outer portion of the second plate being provided with a slot, an end portion of the first plate being provided with an outstanding headed lug insertible through the slot of the second plate to hold the second plate in one of its two positions.

In testimony whereof I hereunto affix my signature.

FRANK M. GINGER.
